(57) **CLAIM**

I claim the ornamental design for an LED light assembly, as shown and described.

DESCRIPTION

FIG. 1 is a perspective view of an LED light assembly showing our new design;

FIG. 2 is a right side elevational view thereof;

FIG. 3 is a left side elevational view thereof;

FIG. 4 is a top plan view thereof; and,

FIG. 5 is a bottom plan view thereof.

The broken lines showing the remaining portions of an LED light assembly are for illustrative purposes only and form no part of the claimed design.
